CODED ENVELOPE TO FACILITATE SORTING

Louis Paston, New York, N. Y.

Application August 18, 1953, Serial No. 374,954

1 Claim. (Cl. 235—61.12)

The present invention relates generally to mailing envelopes and postal cards, and, more particularly, to envelopes and cards bearing coded indicia to facilitate sorting thereof by automatic machinery.

In modern mass-scale advertising practice, it is customary for large organizations and firms to mail promotional literature for a given product or service to every individual named on a selected mailing list of prospects, and to enclose in each letter a self-addressed and stamped return envelope or post card. The recipient of the letter is usually urged to reply by filling out a simple form and to return the completed form in the enclosed envelope. For example, in a campaign to increase the circulation of a magazine, a soliciting letter may be mailed to many thousands of potential subscribers in various parts of the country. Included with the letter is a self-addressed post card to be filled out and signed by the new subscriber in order to place his order. Circular letters of this type constitute a substantial portion of the daily mail in many homes. The response to such circular letters frequently results in a flood of return letters or cards which are first received at local post offices throughout the country where they must be sorted according to state and city, for transmission to the appropriate postal district in the locale of the addressee. Such sorting is performed manually by postal clerks, who must handle each letter separately in order to read the address. This sorting operation, by reason of the huge quantity of mail involved, is time consuming and costly. Moreover, manual sorting is inefficient and many letters are misdirected so that their ultimate delivery to the proper destination may be unduly delayed.

Accordingly, it is the principal object of the present invention to provide a mailing envelope or post card bearing coded indicia adapted to facilitate mechanical sorting by automatic machinery.

More particularly, it is an object of the invention to provide a mailing envelope or card having printed thereon a code field constituted by a series of rows or columns of blank marked-off areas in the configuration of squares or circles. The marked-off areas are, in selected instances, darkened or perforated in accordance with a given code representing, for example, the city and zone of the addressee.

Still another object of the invention is to provide an envelope having a relatively stiff end portion on which is imprinted a code field constituted by rows of columns of circles or squares. In a preferred embodiment of the invention, the stiffened portion is formed by pasting together the front and back sheets of the envelope.

Yet another object of the invention is to provide an envelope having on one stiffened end portion thereof a series of columns providing a coded indicia of the city and zone of the addressee, the envelope also having printed thereon the complete address of the addressee to facilitate sorting and routing of the letter.

Also an object of the invention is to provide a post card on which the complete address of the addressee is in

2

coded form to facilitate the automatic sorting and routing of the card.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

10 Fig. 1 is a front view of a coded envelope in accordance with a first preferred embodiment of my invention.

Fig. 2 is a sectional view taken along lines 2—2 in Fig. 1.

15 Fig. 3 is a front view of a coded envelope in accordance with a second preferred embodiment of my invention.

Fig. 4 is a front view of a coded post card in accordance with a third embodiment of my invention.

20 Fig. 5 separately shows a stiffening element for an envelope.

Referring now to the drawings and, more particularly, to Fig. 1, there is shown a business reply envelope 10, in accordance with the invention, having imprinted thereon at the upper left-hand corner, three spaced parallel lines 11 to be filled in by the addressor with his name and address, the central portion 12 of the envelope having the name and address of the addressee imprinted thereon. At the right-hand end portion of the envelope is imprinted below the customary stamp or mailing permit 13, 30 a rectangular code field 14. The code field 14 is constituted by three parallel vertical columns 15, 16 and 17 of marked-off areas in the form of oblong circles, each column consisting of ten spaced circles. Adjacent the left side at each circle is a digit, the circles in each column being numbered successively 1—2—3—4—5—6—7—8—9—0 from the bottom up.

35 In order to stiffen the right-hand end portion of the paper envelope which includes the code field 14, as shown in Fig. 2 the front sheet 18 and the rear sheet 19 of the envelope at the right-hand end portion, are pasted or glued together by an adhesive layer 20 to produce a relatively rigid strip on which the code field is imprinted. If preferred, for additional stiffening, a relatively rigid rectangular paper card, such as card 33 shown in Fig. 5, 40 may be inserted between sheets 18 and 19 and glued therebetween. As a further modification, card 33 may be glued only to sheet 18 so as to permit the full interior use of the envelope.

45 The envelope having the code field is intended to be used in conjunction with an automatic sorting machine of the type disclosed, for example, in the patent to Ayres et al., 2,056,382, issued October 6, 1936, in which a code field is adapted to be analyzed by a machine having light sensitive elements and the envelope is sorted in accordance with the code markings. For this purpose, selected blank circles are darkened with ink or black pencil. The darkening of the circles may, of course, be printed in. The field is analyzed by a light scanning device, and sorting elements are controlled in accordance with the combination of spots marked upon the envelope.

50 In practice, column 15 may be reserved for a code signifying the city for which the letter is destined, and columns 16 and 17 may be reserved for the zone in the city. Let us assume, for example, that in accordance with a prearranged code, number 1 designates Washington, D. C.; number 2, New York city; number 3, Boston, etc. In Fig. 1 it will be seen that in column 15, circle 2 is darkened; in column 16, circle 1 is darkened; and in column 17, circle 6 is darkened. This code combination, therefore, designates New York, zone 16. Thus, 55 at any given post office, when envelopes of the type shown in Fig. 1 are run through the machine, all envelopes bear-

ing the code 2-1-6 will be segregated from all other envelopes for delivery to the postal district for the indicated New York zone. At that point the address will be read for delivery to the exact destination.

The machine may also be adapted to cancel the attached stamp on the envelope as well as performing a sorting operation. While only three code columns have been shown, it is to be understood that a greater number may be used for more selective sorting of the mail. Thus a special permit may be granted to a given firm having mail orders in bulk quantities, the permit assigning, for instance, the code number 15 for the firm. Two additional columns may be provided for this code number whereby the machine will sort out the appropriately coded mail for delivery directly to the firm. It is to be understood that any standard size envelope may be used for this purpose, only one end portion of the envelope being stiffened for purposes of carrying a code field thereon.

In lieu of a code field wherein the marked-off areas are darkened, a code field may be used in which the marked-off areas are punched out or perforated in accordance with a prearranged code. Thus in the modified envelope shown in Fig. 3, a code field 21 is formed at the right-hand end of the envelope 22 below the stamp. The code field 21 is imprinted on a stiffened strip in the manner described in connection with Figs. 1 and 2.

Code field 21 is constituted by three vertical columns 23, 24 and 25, of spaced rectangular marked-off areas, each column including ten such areas, each area having a digit adjacent thereto. By punching-out a selected area in each column, a code formed by openings or windows is produced. Thus the selected digit in column 23 may represent the city and that in columns 24 and 25 the zone. For the purpose of sorting out such envelopes, an automatic machine of the type described in the patent to Maul, 2,209,414, issued July 30, 1945, or a machine of the type described in the patent to Ford, 1,633,936, issued June 28, 1927, may be utilized, in which the code field is analyzed by sensing brushes extending through the windows in the field.

The full address of the addressee may be expressed solely in the form of code indicia. Thus in Fig. 4, a post card 26 is provided having a rectangular field 27

providing code indicia for the full address. The code indicia are defined by parallel horizontal rows of oblong marked-off areas 28 to 32. Rows 28 and 29 may be used to indicate the firm name by a designated code number, row 30 may be reserved for the code designation for the city, and rows 31 and 32 may be reserved for the zone. Inasmuch as the post card is generally made of relatively stiff material, additional stiffening is ordinarily not essential.

10 While I have illustrated and described the preferred embodiments of my invention, it is to be understood that I do not limit myself to the precise constructions herein disclosed and the right is reserved to all changes and modifications coming within the scope of the invention 15 as defined in the appended claim.

Having thus described my invention, what I claim as new, and desire to secure by United States Letters Patent is:

20 A business reply envelope, comprising rectangular front and rear paper sheets, an adhesive layer secured to one end portion of one of said sheets at the inner side thereof to form a relatively stiffened strip portion, and a rectangular card inserted between said sheets and secured to said adhesive layer to reinforce said stiffened 25 portion, said card being unattached to the other of said sheets so that the entire interior of the envelope defined by said sheets is open and available for use, said one sheet bearing coded marks at the exterior thereof along said stiffened portion, said marks being scannable by photo- 30 sensitive means.
